UNITED STATES PATENT OFFICE

GRAEME MACDONALD, OF SAN FRANCISCO, CALIFORNIA

BERRY BASKET

Application filed March 24, 1928. Serial No. 264,311.

My invention relates, generally, to berry-baskets made of veneer slices, as they are termed in the art, and, in particular, to one-piece baskets.

The objects of my invention are, briefly stated, first to insure their proper shape when filled, in order to adapt them for safe nesting in transportation, and, second to insure them against spreading under the weight of the load when lifted.

To these ends my invention consists essentially in an improved staple, termed in the art a stitch, and in the manner of its application, all of which together with the details of the advantageous results desired and secured, I shall herein fully disclose, reference being had to the accompanying drawings, in which—

Fig. 1 is a plan of the blank or veneer slice from which my one-piece basket is made.

Fig. 2 is an isometric view of my improved one-piece berry-basket.

Fig. 3 is a fragmentary plan view showing the beneficial effect of my improved basket (Fig. 2) in nesting for transportation when filled.

Fig. 4 is a horizontal section, enlarged, of one of the ends of my basket, showing the improved "stitch" and the positive, tight clinching of its extremities.

A, in Fig. 1, designates the blank, which to the trade is known as a veneer-slice and from which my one piece berry basket is made. It is slit on the full lines $x-x$ and is creased for folding on the dotted lines $y-y$. The middle portion of the blank forms the bottom 1 and the inner end members 1^a of the formed basket, while the side portions from the sides 2 of the basket and the flaps 2^a which overlie the end members 1^a of the middle portion.

The end member 1^a and the flaps 2^a are secured together by a staple, which to the trade is known as a "stitch". It is a piece of wire 4 which exteriorly crosses the overlapping flaps 2^a, penetrates them and the end members 1^a, and its ends are bent down upon the inner surface of the members 1^a at 4^a, Fig. 2.

50 A basket in common use made from the

blank of Fig. 1 has non-bulging ends; that is said ends are substantially flat planes at right angles with the sides. If, in use, this relation of the ends to the sides could be preserved there could be no objection to the container. But the veneer slice or blank A is relatively frail and yielding, and the stitch is usually of light wire and not pressed in with maximum security; wherefore when filled with berries, the ends of the basket 55 bulge outwardly under the pressure of the load, and when packed for transportation end to end they do not fit or nest closely enough to maintain their proper position, but are unstable and ride up against each other 60 and thus prevent or destroy their packed relation.

My first improvement will now be clearly understood, reference being made to Fig. 2. It lies in the intentional initial inward arching or curving of the ends of the basket, due to the inward arching or bending of the stitch 70 4. This stitch is made of relatively heavier wire and is appreciably longer than the stitch commonly used. In applying it, the stitch is pressed in with sufficient force to bend it inwardly and thus to normally arch inwardly the ends of the basket, Figs. 2 and 4, to such a degree and with such pressure that, subsequently, under the weight of the load, the ends 75 will be forced outwardly to a flat plane, and will thus lie and remain close together in transportation, as I have shown in Fig. 3.

My second improvement may be explained as follows. It is not the practise in applying the relatively light stitch of the common basket to press it with such force as to cause its bent ends to clinch the members 1^a and flaps 2^a so tightly as to prevent their relative movement. It sometimes happens that the 80 creasing folds between the sides 2 and the bottom 1, are weak enough to open into slits, and then when the basket is lifted, the weight of the load will cause the central portion and the side portions to separate by turning 85 pivotally about the ends of the stitch, and thus opening the slits wide enough to injure or spill the berries. To guard against this contingency, it has been the practise in some cases to put in additional stitches in each end, 90 95 100

but this adds to the cost in labor and material.

By my improvement I secure the desired result by pressing in the stitch 4 with such force that its bent ends 4^a will tightly clinch the parts together, and thus prevent any pivotal relative action between said parts. This I have shown in Fig. 4.

I claim:

1. A berry-basket comprising a blank, the central portion of which forms the bottom and ends of the basket, and the side portions form the sides and overlying flaps of the ends; and a clinching staple penetrating said flaps and ends and having its body inwardly 15 arched to arch the basket ends normally inwardly.
2. A berry-basket comprising a blank, the central portion of which forms the bottom and ends of the basket, and the side portions form 20 the sides and overlying flaps of the ends; and a clinching staple penetrating said flaps and ends and having its body inwardly arched to arch the basket ends normally inwardly and its extremities tightly clinched to prevent 25 pivotal relative movement between said ends and flaps.

In testimony whereof I have signed my name to this specification.

GRAEME MACDONALD.
